UNITED STATES PATENT OFFICE

ELMER R. POPE, OF HAMILTON, MASSACHUSETTS, ASSIGNOR TO UNITED SHOE MACHINERY CORPORATION, OF PATERSON, NEW JERSEY, A CORPORATION OF NEW JERSEY

NAIL DISTRIBUTING APPARATUS

Application filed July 6, 1928. Serial No. 290,794.

My invention relates to apparatus for delivering nails or like fastenings, and is particularly concerned with apparatus by which these fastenings are supplied to blocks or other receivers, from which they are to be utilized in connection with such inserting machines as those employed for loading or attaching heels for shoes.

In Letters Patent of the United States No. 1,325,752, granted December 23, 1919 on application of Joseph H. Pope, is disclosed a distributing apparatus of the character indicated above. In this, nails from a vibratory raceway-structure are delivered in groups by a discharge device through tubes and a foot-bar in which the lower extremities of the tubes terminate, to a block having a plurality of series of receiving openings. The block is fed beneath the tubes step by step, so that all its series of openings are supplied with nails. Then the block is removed from the distributor for use in a nailing machine. Occasionally, in the use of a distributing apparatus, nails will catch in the delivering conduits and must be freed manually. This clogging sometimes takes place at the juncture of the foot-bar and block, a caught nail lying in both. Under these conditions, the block is locked against movement, and, since it cannot be drawn out, it has been the practice to remove the tubes from the foot-bar, so access is had to the passages in the latter for releasing the caught nail or nails. An object of this invention is to facilitate this clearing operation. To this end, I provide a conduit through which the nails enter the receiving block points downward, said conduit having a portion movable upon the withdrawal of the block in a direction transverse to the travel of the nail through the conduit. This movable portion is arranged for actuation by a nail lying in both the block and conduit to permit the passage of said nail from the latter. Herein, the movable portion is shown as a yieldable wall preferably normally closing a side of the passages in the foot-bar through which the tubes deliver. With such an organization, if a tube is clogged between the foot-bar and block, the latter is simply drawn out. This forces the retained nail

against the foot-bar wall, which yields so that the removal of the block is not interfered with. The conduit may then be cleared as is most convenient.

Because, among other reasons, of the desirability of removing the tubes from the foot-bar for clearing the passages, it has been customary to make these tubes flexible by forming them of helices of wire. As a result of handling, the convolutions of the helices become displaced laterally, and, instead of the properly smooth nail-conducting interior surface, they assume a stepped relation, and the projections may catch and retain nails. Another object of this invention is to remove the possibility of such action by an assembly of tubes having permanently smooth interiors and convenient to manipulate as a unit. When, as with the nail-releasing arrangement just outlined, it becomes unnecessary to remove the tubes to relieve clogging, they may be made rigid, and therefore with smooth interior surfaces with which the conducted nails contact. These tubes are preferably formed into an assembly by bars which retain their opposite extremities in fixed relation to one another. They may therefore be removed from the apparatus as a unit, and readily returned to their true relation to the conduits which deliver to their upper extremities and the openings in the foot-bar into which they discharge. The position of the assembly with reference to the foot-bar may be fixed by the reception of a plurality of the assembled tubes in openings in said foot-bar. The upper extremities of these tubes are preferably maintained in co-operation with the discharge-conduits of the distributor by the foot-bar, which is movable toward and from said discharge-conduits, as through the agency of a spring acting upon the latter. The upper portion of the assembly may be removably held in registration with the discharge-conduits by at least one spring-clip.

A particular form of my invention is illustrated in the accompanying drawings. Herein,

Fig. 1 is a front elevation of a portion of

a nail-distributor including my improved foot-bar and nail-tube assembly;

Fig. 2 is an enlarged vertical section on the line II—II of Fig. 1; and

5 Fig. 3 is a broken plan view of the top of the tube-assembly with a portion of its upper retaining means.

The general structure shown in the drawings resembles that of the patent already mentioned, and will not be described in detail. At 10 is seen the casing of the discharge device, through conduits 11 in which loads of nails are delivered from raceways (not illustrated). A perforated block, to be supplied 10 with a plurality of these loads, appears at 12, it being mounted upon the carriage 14, fed forward step by step in its ways by ratchet mechanism indicated at 16. Mounted upon the carriage, above the block, is a tem- 15 plet 18, which guides nails to the block-openings 20 and prevents the longer nails from becoming unduly inclined. Though this templet is a part of the distributing apparatus and is not removable with the block, 20 for the purposes of this invention it is, in effect, a portion of said block and will be so referred to hereafter.

The nails delivered by the discharge device pass through a tube-assembly A, there being in the assembly a tube 22 for each opening 20 of a series extending transversely of the block. I prefer these tubes to be so drawn of metal that they are rigid, their extension from registration with conduits of 25 the discharge device to vertical alinement with a corresponding opening in the block being obtained by bending them in such a manner as to minimize clogging. The correct spacing of the tubes and their retention 30 as a unitary structure is effected by an upper bar B and a lower bar 24. The bar B includes a rear section 26, in the forward edge of which is a series of V-depressions to receive the upper extremities of the tubes 22, 35 which are thereby spaced for alinement with the discharge-conduits. In the depressions, the tubes are clamped by a front section 28 of the bar secured to the section 26 by screws 30. The bar 24 is provided with vertical 40 openings to receive the lower delivery-ends of the tubes, which are thereby separated from one another to correspond to a series of openings 32 in a foot-bar 34. Certain of these tubes, as the two outer ones, are en- 45 gaged by set-screws 36 threaded through the bar, which is thus held in place. These same outer tubes are shown as extending below the foot-bar at 38, so they enter openings 32. This holds the lower portion of the tube-as- 50 sembly from lateral displacement out of its normal registration with the foot-bar open- 55 ings. At the under side of the casing 10 are spring-clips 40, 40 constructed and arranged to engage the upper portions of the outer 60 tubes 22. These normally retain the assem- 65 blies tubes in alinement with the discharge conduits, but will yield to permit the as- sembly to be tipped forward for removal.

The foot-bar 34, which furnishes the lower support of the tube-assembly A, is, as in the previously mentioned patent, carried at the forward extremities of levers 42, and is joined by the link 44 to a transverse lever 46. When the nails to be used are not so long as to project above the block, or, as in the present in- 70 stance, above the block with its templet, it is unnecessary to lift the foot-bar to allow the block to be stepped forward. Under these conditions, the rigid assembly A produces no interference, and oscillating mechanism for the lever 46 is unnecessary. With this lever, however, I prefer to associate a spring 48. This acts to raise the foot-bar so it is pressed against the lower portion of the tube-assem- 75 bly A, maintaining the tube-extensions 38 in the foot-bar openings and holding the assem- 80 bly in place. The yield of this spring 48 al- 85 lows the foot-bar to be somewhat lowered to facilitate the separation of the assembly from the distributor.

Were such a clogging to occur as is shown in Fig. 2 of the drawings, the upper nail N would prevent the forward travel of the carriage 14 to give access to the seat of the trouble, since this nail would contact with both 90 the foot-bar and the block. It would ordi- 95 narily be necessary to take out the tube-assem- bly and work through the opening in the foot- 100 bar. I minimize the effort required for clear- 105 ing the nail N by furnishing, in the front of the foot-bar, a section which may be caused to yield by a force acting through a retained nail. Pivoted at 50 on the upper part of the front wall of the bar 34 is a section 52, which furnishes the wall at the forward side of the lower portion of the openings 32. A spring 54 is so connected that its tension may be ap- 110 plied at the opposite sides of the pivots to hold the section either closed or open. Nor- 115 mally, the wall-section 52 is in the position illustrated in full lines in Fig. 2. When clog- 120 ging occurs in the delivery to the block 12, the operator draws out the carriage 14 in its ways. If the retained nail is as indicated at N, the movement of the block, carrying the point of the nail with it in a direction trans- 125 verse to the vertical conduits which terminate in the foot-bar, will force the head against the section 52. This yields and is thrown to its open position, shown in dotted lines in Fig. 2, to be there held by the spring 54, permitting the block to travel forward unimpeded. The caught nail may readily be removed, the car- 130 rriage restored to its receiving relation, and the wall-section lowered for a continuation of the loading operation.

Having described my invention, what I claim as new and desire to secure by Letters Patent of the United States is:

1. In a nail-distributing apparatus, a mov-

130

able nail-block arranged for association with the apparatus to receive its load of nails, and a conduit from which the nails may pass to the block points foremost, the conduit having a movable portion arranged for actuation by contact of a nail lying in both the block and conduit, such actuation occurring upon the withdrawal of the block in a direction transverse to the travel of the nail through the conduit.

2. In a nail-distributing apparatus, a movable nail-block arranged for association with the apparatus to receive its load of nails, and a conduit extending transversely to the direction of movement of the block and through which nails may pass to said block points foremost, the conduit having a yieldable wall arranged for movement in the direction of withdrawal of the block by a nail lying in both the block and conduit.

3. In a nail-distributing apparatus, a movable nail-block arranged for association with the apparatus to receive its load of nails, a nail-tube extending transversely of the direction of movement of the nail-block and delivering nails to the block points foremost, and a holder for the tube adjacent to the block, said holder having a yieldable wall arranged for movement in the direction of withdrawal of the block by a nail lying in both the block and conduit.

4. In a nail-distributing apparatus, a nail-block provided with a series of nail-receiving openings and being removable from the apparatus, a series of tubes delivering to the openings, a foot-bar in which the tubes terminate above the block and having nail-passages alined with the tubes, said foot-bar having a wall movable in the direction of removal of the block, and a spring connected to the wall and arranged to both hold it normally in place upon the foot-bar and to maintain it spaced from said bar with the sides of the passages open.

5. In a nail-distributing apparatus, a nail-tube assembly comprising a series of rigid tubes, and bars retaining the opposite extremities of the tubes in fixed relation to one another, said assembly being separable from the apparatus as a unit.

6. In a nail-distributing apparatus, a nail-tube assembly comprising a series of rigid tubes, means for retaining the tubes in fixed relation to one another removable from the apparatus as a unit, and a foot-bar provided with openings arranged to receive a plurality of the tubes of such unitary assembly and fix it in a predetermined position upon the foot-bar.

7. In a nail-distributing apparatus, a nail-tube assembly comprising a series of rigid tubes, means for retaining the upper and lower extremities of the tubes in fixed relation to one another, discharge-conduits for delivering nails to the upper extremities of

the tubes, and a foot-bar contacting with the lower ends of the tubes and movable toward and from the discharge-conduits, said foot-bar being arranged to maintain co-operation between the tubes and discharge-conduits. 70

8. In a nail-distributing apparatus, a nail-tube assembly comprising a series of rigid tubes, means for retaining the tubes in fixed relation to one another, discharge-conduits for delivering nails to the upper extremities 75 of the tubes, a foot-bar contacting with the lower ends of the tubes, and a spring acting upon the foot-bar and arranged to force the tubes into co-operation with the discharge-conduits.

9. In a nail-distributing apparatus, a nail-tube assembly comprising a series of rigid tubes, bars retaining respectively the upper and lower extremities of the tubes in fixed relation to one another, discharge-conduits 85 for delivering nails to the upper extremities of the tubes, a foot-bar contacting with the lower ends of the tubes and arranged to maintain co-operation between the tubes and discharge conduits, and a spring-clip arranged to engage the upper portion of the assembly. 90

In testimony whereof I have signed my name to this specification.
